(57) **CLAIM**

The ornamental design for a wireless microphone and charging box assembly as shown and described.

DESCRIPTION

FIG. 1 is a front, right and bottom perspective view of a wireless microphone and charging box assembly, showing my new design.

FIG. 2 is an enlarged view of detail 2 in FIG. 1.

FIG. 3 is an enlarged view of detail 3 in FIG. 1.

FIG. 4 is a front, right and bottom perspective view of the charging box of the wireless microphone and charging box assembly shown in a closed position.

FIG. 5 is a rear, left and top perspective view of the charging box of FIG. 4.

FIG. 6 is a front elevation view of the charging box of FIG. 4.

FIG. 7 is a rear elevation view of the charging box of FIG. 4.

FIG. 8 is a left side elevation view of the charging box of FIG. 4.

FIG. 9 is a right side elevation view of the charging box of FIG. 4.

FIG. 10 is a top plan view of the charging box of FIG. 4.

FIG. 11 is a bottom plan view of the charging box of FIG. 4.

FIG. 12 is an enlarged view of detail 12 in FIG. 4.

FIG. 13 is another front, right and bottom perspective view of the charging box of FIG. 4 in an open position.

FIG. 14 is a front, right and top perspective view of a receiver of the wireless microphone and charging box assembly in FIG. 1.

FIG. 15 is a rear, left and bottom perspective view of the receiver of FIG. 14.

FIG. 16 is a front elevation view of the receiver of FIG. 14.

FIG. 17 is a rear elevation view of the receiver of FIG. 14.

FIG. 18 is a left side elevation view of the receiver of FIG. 14.

FIG. 19 is a right side elevation view of the receiver of FIG. 14.

FIG. 20 is a top plan view of the receiver of FIG. 14.

FIG. 21 is a bottom plan view of the receiver of FIG. 14.

FIG. 22 is an enlarged view of detail 22 in FIG. 14.

FIG. 23 is a front, right and bottom perspective view of a microphone of the wireless microphone and charging box assembly in FIG. 1.

(Continued)

FIG. 24 is a rear, left and top perspective view of the microphone of FIG. 23.
 FIG. 25 is a front elevation view of the microphone of FIG. 23.
 FIG. 26 is a rear elevation view of the microphone of FIG. 23.
 FIG. 27 is a left side elevation view of the microphone of FIG. 23.
 FIG. 28 is a right side elevation view of the microphone of FIG. 23.
 FIG. 29 is a top plan view of the microphone of FIG. 23.
 FIG. 30 is a bottom plan view of the microphone of FIG. 23; and,
 FIG. 31 is an enlarged view of detail 31 in FIG. 23.
 The dashed broken lines depict portions of the wireless microphone and charging box assembly that form no part of the claimed design. The dot-dash broken lines in FIGS. 1-4, 12, 14, 22-23, and 31 depict the boundaries of the enlargements that form no part of the claimed design.
